UNITED STATES PATENT OFFICE.

STEPHEN F. BRIGGS, OF MILWAUKEE, WISCONSIN, ASSIGNOR TO BRIGGS & STRATTON COMPANY, OF MILWAUKEE, WISCONSIN, A CORPORATION OF WISCONSIN.

SWITCH FRONT PLATE.

1,280,655.

Specification of Letters Patent.

Patented Oct. 8, 1918.

Application filed September 13, 1915. Serial No. 50,539.

To all whom it may concern:

Be it known that I, STEPHEN F. BRIGGS, a citizen of the United States, and resident of Milwaukee, in the county of Milwaukee 5 and State of Wisconsin, have invented new and useful Improvements in Switch Front Plates, of which the following is a description, reference being had to the accompanying drawings, which are a part of this 10 specification.

This invention has for its object to provide a simple means for connecting the ornamental polished front-plate of a switch with the switch frame in such a manner 15 as to be invisible and not detract from the ornamental appearance.

With this object in view the invention consists in so forming the front-plate that the openings for the securing screws are 20 countersunk and receive tubular rivets through which may pass the securing screws for holding the switch to the dash-board of an automobile or other support, thus permitting the heads of the securing screws to 25 lie substantially flush with the polished surface of the front-plate and entirely obscure the connecting means.

With the above and other objects in view the invention consists in the front-plate connector for switches as herein claimed and 30 all equivalents.

Referring to the accompanying drawings in which like characters of reference indicate the same parts in different views:

35 Figure 1 is the front view of a switch front-plate provided with a connecting means of this invention, one corner thereof being broken away to show the construction of the switch frame and the connecting 40 means therefor;

Fig. 2 is a rear view thereof;

Fig. 3 is a transverse sectional view of the switch frame and its front-plate; and,

Fig. 4 is a detail sectional view through 45 one of the front-plate connectors showing the securing screw in dotted lines.

In these drawings 10 indicates an ornamental front-plate for a switch such as an ignition and lighting switch for automobiles 50 and the like, though the invention is not confined to switches for any particular purpose. In the switch shown this ornamental front-plate consists of a thin sheet metal plate pressed to form a flanged edge with 55 a deep bevel so that the main portion of

the front-plate is spaced from the surface of the dash-board or other switch panel to which it is fitted and behind the switch plate is secured the front of the switch frame 11 which may include a switch box 60 12 containing the switch mechanism not shown. At each corner the front-plate 10 has a depressed or countersunk opening 13 terminating in an internal annular flange 14 while each corner 15 of the front portion of the switch frame 11 is bent downwardly or offset to a plane parallel with said front portion so as to bear against the rear surface of the flange 14 while said main portion of the front of the frame preferably, though not necessarily, bears against the rear of the main portion of the front-plate as shown to reinforce it. These offset corners 15 have openings in alinement with the openings within the flanges 14 and tubular rivets 16 pass through such alined openings with their ends overturned against the front of the flanges 14 and against the rear of the corners 15 of the switch frame respectively to securely hold the front-plate 80 to the switch frame. The securing screws 17 for securing the switch to its support pass through the tubular rivets 16 with their heads occupying the depressed or countersunk portion of the openings 13 in 85 front of the rivets 16 so that said rivets are entirely hidden from view.

The switch front-plate securing means of this invention may be quickly and easily applied without danger of marring the polished surface of the front-plate as when rivets or screws are employed for the purpose and are entirely hidden from view. The rear flanges of the tubular rivets are preferably in the plane of the bearing edge 95 of the surrounding flange of the front-plate so as to bear against the surface to which the front-plate is secured and thus the tightening of the securing screws 17 may be effected without danger of dishing or warping 100 the thin sheet metal front as the pressure of the heads of the securing screws is taken directly by the tubular rivets in bearing contact with the surface of the support.

By means of the invention the front-plate and switch frame construction may be made strong and durable with a low cost of manufacture and the front-plate may be neat and ornamental in its appearance without showing its securing means.

What I claim as new and desire to secure by Letters Patent is:

1. A front plate connector for switches, comprising the combination with a front plate having cylindrical depressions with internal flanges of a switch frame behind the front plate, and tubular rivets connecting the switch frame with the front plate and having external flanges contained within the cylindrical depressions and seated on the internal flanges thereof, said cylindrical depressions adapted to contain the heads of securing screws to hide the rivets from view.

2. A switch front-plate connector, comprising the combination with a front-plate having a cylindrical depression with an internal flange, of a switch frame bearing against the rear of the internal flange, a tubular rivet connecting the internal flange with the switch frame and adapted to receive a securing screw and be hidden from view by the head thereof contained within the depression of the front-plate.

3. A switch front-plate connector, comprising the combination with a flanged front-plate having a countersunk opening forming a recess with an internal flange, of a switch frame bearing against the rear of the internal flange, a tubular rivet connecting the internal flange with the switch frame, the rear surface of the tubular rivet lying in the same plane as the edge of the front-plate

to bear against a supporting surface to which the front-plate is secured, and a securing screw passing through the tubular rivet with its head contained in the recess of the countersunk opening of the front-plate and bearing against the tubular rivet.

4. A switch front-plate connector comprising the combination with an ornamental flanged front-plate having depressed or countersunk openings forming recesses with internal flanges, of a switch frame having a front portion bearing against the rear surface of the front plate and offset portions bearing against the internal flanges of the recesses of the front plate and having openings registering with the openings of the front plate, tubular rivets passing through said openings and having external flanges engaging the internal flanges of the front plate and the rear surface of the offset portions of the switch frame respectively, and securing screws passing through the tubular rivets with their heads fitting within the recesses of the front-plate and bearing against the tubular rivets and hiding the tubular rivets from view.

In testimony whereof, I affix my signature, in presence of two witnesses.

STEPHEN F. BRIGGS.
